UNITED STATES PATENT OFFICE.

ALEXANDER M. SCHNEIDER, OF NEW YORK, N. Y.

ADJUSTABLE TAPE.

1,197,070.

Specification of Letters Patent. Patented Sept. 5, 1916.

Application filed January 18, 1916. Serial No. 72,656.

To all whom it may concern:

Be it known that I, ALEXANDER M. SCHNEIDER, a citizen of the United States, and a resident of New York city, in the 5 county of Bronx and State of New York, have invented certain new and useful Improvements in Adjustable Tape, of which the following is a specification.

This invention relates to an adjustable 10 tape which by a comparative short movement of its adjusting means, is lengthened or shortened for three times the path of said adjusting means.

The invention is well applicable to a tape 15 extending along the waist line of a skirt or similar garment as it permits the waist measure to be materially changed with a small change in the position of the adjusting means.

20 In the accompanying drawing: Figure 1 is a perspective view of the upper part of a skirt provided with an adjustable tape embodying my invention; Fig. 2, is a diagram illustrating the run of the 25 tape; Fig. 3, a longitudinal section through part of the tape pocket; Fig. 4, a section on line 4—4 Fig. 3; Fig. 5, a cross section on line 5—5 Fig. 1, and Fig. 6, a cross section on line 6—6 Fig. 1.

30 The body of a skirt or other garment 1, is provided at its top or waist line, with a tubular pocket 2. This pocket is closed along its lower edge at its ends, but is open 35 between such ends, so that access may here be obtained to its contents. Within pocket 2, is housed, a waist band or tape 3, the ends of which are attached to the garment by seams 4, such ends protruding from the ends of the pocket, where they may be connected 40 to each other by suitable fasteners 5. At the front of the garment, the waist band is tripled in a peculiar manner, along its right as well as along its left side which sides are exact duplicates, so that the description of 45 one will apply to the other.

Coöperating with say the right side of the waist band are four slides or locking members 6, 7, 8 and 9 which are alike in construction, each slide being formed of a frame 50 having a pair of slots, and a cross bar intermediate the slots. The waist band passes from slide 6 to slide 7, back through slide 6, forward to slide 8, back through slide 7, forward to slide 9, and thence through 55 slides 8 and 9, to eventually pass to slide 9 on the left side of the garment. In this

way, the band is made of triplex thickness between the slide pair 6 and 7 on the one hand, and the slide pair 8 and 9 on the other hand. The construction is 60 such that the two members of each slide pair are alined and are place directly against one another face to face, so that they will tightly clamp the band threaded therethrough, the clearance shown in Fig. 2, being 65 merely diagrammatic and for the purpose of better illustrating the run of the band. Slides 7, are attached to the garment by tabs 10, so that they cannot be moved, while the slides 8 and 9 are accessible 70 through the open portion of pocket 2. When say the right side of the waist is to be lengthened the slides 8 and 9 are moved to the right, whereby the three ply portion 75 of the waist band is diminished, the overall portion of the band is correspondingly increased, and the tucks 11 formed at the back of the garment, between the slides 6 and 7 on the one hand, and the end seam 4 on the other hand are more or less flattened. When 80 the right side of the waist is to be shortened, the band is drawn to the left through slide 7, and then slides 8 and 9 are pushed to the left, so that the three ply portion of the band is increased, its overall length is correspondingly diminished, and the tucks 85 11 are gathered to the extent desired. The left side of the waist is of course adjusted in a similar manner.

It will be seen that there is always maintained between the slide pairs 8, 9 and 6, 7 respectively, a tri-folded section of the tape. Therefore, a comparatively small movement of the slides will either release or gather up such a length of tape, as will cause its released or folded portion to be equal to three times the path of the slides. In this way, a comparatively short movement of the slides will suffice to either pack the tucks 95 tightly or straighten them out so that the length of the open pockets 2 may be reduced to a minimum, and that a quick response to the movement of the slides is insured.

The garment may be adjusted at its waist in a most simple manner, and after being 100 so adjusted, is securely locked in position. The device is invisible though readily accessible and does not add any objectionable thickness to the waist line of the wearer.

I claim:

1. A tape, a first pair of contacting slotted slides, and a second pair of contacting

110

slotted slides mounted on the tape, said tape forming a three fold section between said slide pairs.

2. A tape, a first pair of contacting slotted slides and a second pair of contacting slotted slides mounted on the tape, said tape passing from one slide of the first pair to

the second slide of said pair, back to the first slide, to the first slide of the second pair, back to the second slide of the first pair, to the second slide of the second pair, to the first slide of the second pair, and back to the second slide of the second pair.

ALEXANDER M. SCHNEIDER.
